UNITED STATES PATENT OFFICE.

JESSE H. LIPPINCOTT, OF SWISSVALE, PENNSYLVANIA.

DESIGN FOR A TABLE VESSEL OR DISH.

SPECIFICATION forming part of Design No. 16,934, dated October 12, 1886.

Application filed April 8, 1886. Serial No. 198,311. Term of patent 14 years.

To all whom it may concern:

Be it known that I, JESSE H. LIPPINCOTT, of Swissvale, in the county of Allegheny and State of Pennsylvania, have invented a new and original Design for Glass Vessels; and I do hereby declare the following to be a full, clear, and exact description thereof.

My new and original design consists in a vessel having the form of a coal scuttle or hod with a raised or indented pattern on its outer surface. It is applicable especially to small ornamental vessels or holders.

In the accompanying drawing, which is a perspective view of a small glass vessel, dish, or holder of my new and original design, *a* indicates the body, which is externally orna-

mented with an indented pattern; *b*, the foot, and *c* the bail. The result is a handsome table article.

What I claim as new and original, and desire to secure by Letters Patent, is—

The design for a table vessel or dish herein shown and described, the same consisting in the hod-shaped vessel or dish having upwardly-flaring sides and an external raised or indented ornamental pattern.

In testimony whereof I have hereunto set my hand this 31st day of March, A. D. 1886.

JESSE H. LIPPINCOTT.
